M. F. FISCHER

ATTACHMENT FOR SCREEN DOORS

Filed March 30, 1923

UNITED STATES PATENT OFFICE.

MAX F. FISCHER, OF ARVADA, COLORADO.

ATTACHMENT FOR SCREEN DOORS.

Application filed March 30, 1923. Serial No. 628,797.

To all whom it may concern:

Be it known that I, MAX F. FISCHER, a citizen of the United States, residing at Arvada, county of Jefferson, and State of Colorado, have invented certain new and useful Improvements in Attachments for Screen Doors; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to an attachment adapted to be applied to a screen door for the purpose of preventing the entrance of flies when the door is being opened and closed.

Flies are recognized to be disagreeable pests as well as carriers of disease, and many different expedients have been resorted to for the purpose of excluding flies from dwelling houses, kitchens and dining-rooms.

The method relied upon at present and which has proven the most satisfactory is to equip all windows with screens and to employ screen doors. In buildings where the windows are properly screened, the only place where the flies may enter is through the doors.

It is well known that where screen doors are used, the flies will gather around the top of the door, as this is where the warm air and the odors from the building leave. When the doors are opened to permit people to leave or enter, the flies will be disturbed and some of them will enter the building.

It is the object of this invention to provide means that can be readily attached to a screen or other type of door and which will serve to prevent flies from entering while the door is open.

My attachment is so designed and constructed that it can be cheaply made and easily and quickly installed by any person having the least experience in handling tools.

In order to better describe my invention, I shall have reference to the accompanying drawing, in which the preferred embodiment thereof is shown, and in which:

Fig. 1 is a perspective view showing a door and door frame equipped with my improved device. 55

Fig. 2 is a section taken on line 2—2, Fig. 1.

Fig. 3 is an enlarged section of the supporting bar.

Fig. 4 is a section taken on line 4—4, 60 Fig. 2.

Fig. 5 is a fragmentary perspective view, partly in section, of my attachment; and

Fig. 6 is a section taken on line 6—6, 65 Fig. 4.

The same reference characters will be employed to designate the same parts throughout the several views.

In the drawings I have shown a door frame having parallel vertical side members 1, a horizontal top member 2 and a sill 3 to which a screen door 4 is hinged. Mounted parallel with the top member 2 and rotatably secured to the side members 1 near the top of the door frame is a spring roller 5, such as is commonly employed in connection with roller shades, the catches of which have been removed or made inoperative. The end pivot 6 is round, while the pivot pin 7 is flattened and engages with a bracket member such as is employed in the corresponding position in mounting a roller shade between the sides of a window frame. The roller and supporting brackets are not illustrated in detail, as they embody nothing new. A cord 8 is wound about the roller in such a direction that when the cord is unwound by pulling the same, it will wind the spring on the roller. The spring in the roller is wound to a suitable tension and 85 the end of the cord connected to the door at a point 9, which is preferably on the level with the bottom of the roller. It is now evident that when the door is moved to open position, the roller is rotated in a direction to wind the spring therein and when the door is released the spring will rotate the roller in the opposite direction and close the door. The roller 5 and cord 8 take the place of the ordinary screen door spring or 90 spring hinges, although spring hinges may be used in addition if desired.

In order to prevent the entrance of flies through the space between the top of the

roller and the frame member 2, I support a rod 10 by means of hooks 11 from the member 2 and fasten to this rod a paper or cloth 12 which is provided at its top with 5 a tubular pocket through which the rod 10 may pass. The paper 12 may have its lower edge cut into strips, as indicated by numeral 13. Directly below the roller 5 I mount a flexible strip 14 which is secured at one end 10 to a bracket 15, which, in its turn, is fastened to the vertical member 1 of the door frame. The relationship of the bracket 15, rod 14 and door frame is such that the rod will be held parallel to the roller a short 15 distance below it. Since the rod 14 is supported at one end only and is flexible, it is evident that it can be made to vibrate in a horizontal plane. Secured to the roller 5, at a point substantially midway between its 20 ends, are two projecting portions or pins which I have indicated by the numeral 16. The pins 16 may be formed by any suitable material, such as wood or steel screws preferably covered with a rubber tube. I have 25 shown a specific embodiment which consists of two substantially identical semi-circular members 17 whose ends 18 are bent outwardly in a radial direction and riveted or otherwise secured together. Over the ends 30 18 I place a short piece of rubber tubing 19 (Fig. 6). The bar or strap 14 is placed so close to the roller 5 that when this rotates, the pins 16 will strike it and cause it to vibrate transversely. I have shown two pins, 35 but it is obvious that a greater or less number may be used.

Secured to the strap or bar 14 is a piece of cloth or paper 20 whose upper edge is doubled over so as to provide an opening 40 through which the bar 14 may pass and after the bar has been inserted within this opening, it may be held in place by means of glue. The lower edge of paper 20 may be cut into a number of narrow strips 21 and 45 may be curved as shown in Figs. 1 and 5 so that they extend lower near the side of the frame where the door opens. By moving the pins 16 longitudinally on the roller, the extent of the vibrations of the rod 15 may 50 be varied, as it is evident that the nearer to the pivot point the pins 16 strike the bar 14 the greater will be its movement.

The operation of my device is as follows: 55 When the parts are assembled in the manner described, the roller 5 will be rotated in one direction when the door is opened and in the other direction when the door closes. As the roller 5 rotates, the pins 16 will strike the bar 14 causing it to vibrate. This vibration 60 will cause the paper 20 and fringes or strips 21 to shake in such a manner that flies will not attempt to pass.

When the paper 12 or 20 wears out or 65 becomes torn, it may be readily replaced by another similar piece.

I want to call particular attention to the vibratory action of my device, as this results in a neater and more effective device than would be the case if the papers were rotated by any means.

Having now described my invention, what I claim as new is:

1. In combination, a door frame; a door pivotally attached to one side thereof and adapted to be opened and closed; a spring roller mounted between the two vertical side members of the door frame; a flexible member wound about said roller and having one end secured to the roller and the other to the door, the relation between the spring roller and the flexible member being such that when the door is opened, the roller will be rotated in a direction tending to wind the spring; a flexible member secured to one side of the door frame and located directly beneath the roller, said flexible member being free to vibrate in a horizontal plane; and projecting portions on the roller adapted to engage the flexible member when the roller rotates and to cause the same to vibrate.

2. In combination, a door frame; a door pivotally attached to one side thereof and adapted to be opened and closed; a spring roller mounted between the two vertical side members of the door frame; a flexible member wound about said roller and having one end secured to the roller and the other to the door, the relation between the spring roller and the flexible member being such that when the door is opened the roller will be rotated in a direction tending to wind the spring; a flexible member secured to one side of the door frame and located directly beneath the roller, said flexible member being free to vibrate in a horizontal plane; projecting portions on the roller adapted to engage the flexible member when the roller rotates and to cause the same to vibrate; and a sheet of thin flexible material secured to 100 said flexible member.

3. In combination, a door frame; a door pivotally attached to one side thereof and adapted to be opened and closed; a spring roller mounted between the two vertical side members of the door frame; a flexible member wound about said roller and having one end secured to the roller and the other to the door, the relation between the spring roller and the flexible member being such that when the door is opened the roller will be rotated in a direction tending to wind the spring; a flexible member secured to one side of the door frame and located directly beneath the roller, said flexible member being free to vibrate in a horizontal plane; projecting portions on the roller adapted to engage the flexible member when the roller rotates and to cause the same to vibrate; and a sheet of thin flexible mate- 115 120 125 130

rial secured to said flexible member, the lower edge of said flexible material being cut into a plurality of strips.

4. In combination, a door frame; a door pivotally attached to one side thereof and adapted to be opened and closed; a spring roller mounted between the two vertical side members of the door frame; a flexible member wound about said roller and having one end secured to the roller and the other to the door, the relation between the spring roller and the flexible member being such that when the door is opened the roller will be rotated in a direction tending to wind the spring; a flexible member secured to one
- 5 side of the door frame and located directly beneath the roller, said flexible member being free to vibrate in a horizontal plane; projecting portions on the roller adapted to engage the flexible member when the roller rotates and to cause the same to vibrate; a sheet of thin flexible material secured to said flexible member, the lower edge of said flexible material being cut into a plurality of strips; and a piece of flexible material between the top of the door frame and the roller.
- 10 15

In testimony whereof I affix my signature.

MAX F. FISCHER.
